UNITED STATES PATENT OFFICE.

JOSEPH G. BAIN, OF PITTSBURGH, AND LASZLO M. STEMPPEL, OF DORMONT, PENNSYLVANIA, ASSIGNORS TO LEWIS FOUNDRY & MACHINE COMPANY, OF PITTSBURGH, PENNSYLVANIA, A CORPORATION OF PENNSYLVANIA.

BRIDLING APPARATUS.

Application filed April 12, 1922. Serial No. 551,766.

To all whom it may concern:

Be it known that we, JOSEPH G. BAIN and LASZLO M. STEMPPEL, both citizens of the United States, residing, respectively, at 5 Pittsburgh, in the county of Allegheny and State of Pennsylvania, and Dormont, in the county of Allegheny and State of Pennsylvania, have invented a new and useful Improvement in a Bridling Apparatus, of 10 which the following is a specification.

This invention relates to bridling apparatus for use in conjunction with rolling mills.

A general object of the invention is to 15 provide bridling apparatus which places under tension a strip of metal being passed through a rolling mill, while avoiding the labor and difficulty incurred in threading the strip through stationary bridle bars.

20 A more specific object of the invention is to provide bridling apparatus, of the nature noted above, which permits regulation of the tension under which the strip is held within wide limits in accordance with the 25 thickness and stiffness of the strip being rolled, or in accordance with the nature of the metal of which the strip is composed.

30 A further specific object of the invention is to provide for any desired tensioning of the strip within such limits.

It is also common practice to roll out 35 metal wires of round or rectangular cross section, and of varying cross sectional area into ribbons. It is desirable that such material, equally with strips be subjected to tension while being passed through the reducing rolls. In the art it is customary to 40 include such forms, as well as the flat forms called strips hereinabove, under the general term of "bars."

A still further object of the invention is, therefore, to provide bridling apparatus embodying the advantages mentioned above 45 which may be arranged or readily adapted for use with bars of round or rectangular cross section as well as with the flat bars more specifically called strips.

In the accompanying drawings Figure 1 50 is a side elevation, showing the bridling apparatus in position on the housing of a rolling mill; Figure 2 is a plan view of the bridling apparatus; Figure 3 is a diagrammatic view illustrating the threading of a strip through the bridling apparatus; Fig-

ures 4, 5, 6, and 7 are similar diagrammatic 55 views illustrating progressive steps in the tensioning of a strip which is being passed through the rolling mill; Figure 8 is a front elevation or apparatus embodying the principles of the present invention which is arranged particularly for the bridling of bars which are round or rectangular in cross section; and Figure 9 is a detail elevation of one form of bar adapted to use with such modified form of the apparatus. 63

In the drawings the reference numerals 1 and 2 designate the side or frame members of the bridle, which are secured in vertical ways 3 of the roll housing 4 by means of bolts 5, so that the bridle as a whole may 70 be adjusted vertically for alignment with the reducing rolls 6 of the rolling mill. These side members 1 and 2 of the bridle are interconnected by means of an immovable bridle bar 7 disposed adjacent the roll 75 housing; and by bridle bars 8 and 9, which are rotatably mounted in the side members 1 and 2 but which are otherwise immovable with respect thereto.

Rotatably mounted in the side frame 1 of 80 the bridle is a short shaft 10 having thereon the operating handle 11 by means of which the shaft may be manually rotated. Rigidly secured to the short shaft 10 is a segmental rack 12, which meshes with a pinion 13 85 keyed or splined on the more outwardly disposed rotatable bridle bar 9. On their opposite ends, beyond the other side member 2, the rotatable bars or shafts 8 and 9 are provided respectively with the intermeshing 90 pinions 14 and 15. When, therefore, the bar or shaft 9 is rotated by means of the meshing of the pinion 13 thereon with the segmental rack 12; the bar or shaft 8 is rotated in an opposite direction by means of 95 the pinions 14 and 15.

The operating mechanism described immediately above is for the purpose of actuating movable bridle bars, which are arranged to cooperate with the bars 8 and 9 100 for placing a strip under tension. One such movable bar 16 is rigidly mounted on the bar or shaft 8 by means of curved arms 17, and another movable bar 18 is rigidly mounted on the bar or shaft 9 by means of 105 the curved arms 19.

It will be seen by reference to Figure 1 of the drawings that the arms 19, by which

the bar 18 is mounted on the shaft 9, are shorter and from arcs of greater curvature than the arms 17 by which the bar 16 is mounted on the shaft 8. Thus the bar 16 when swung describes the arc A—A, while the bar 17 when swung describes the arc B—B of lesser radius than the arc A—A. It will also be seen by reference to Figure 2 of the drawings that the bar 16 is longer than the bar 19, and that its mounting arms 17 are disposed outwardly of the mounting arms 19 of the bar 18.

Because of the structure described immediately above the bars 16 and 18 are enabled to pass each other when rotated in opposite directions; and it will also be seen that the bar 18, mounted on the shorter and more curved arms 19, will pass the point C at which the arcs A—A and B—B intersect before the bar 16 arrives at such point.

In use of the apparatus the strip of metal 20, which is to be rolled, may be led freely through the various bars of the bridle and gripped by the reducing rolls 6. This position of the strip is illustrated in Figure 3 of the drawings; which shows the strip lying beneath the stationary bridle bar 7 and rotatable bridle bars 8 and 9, and lying above the swinging bridle bars 16 and 18.

When the strip 20 has been gripped by the rolls the bars 16 and 18 are swung in opposite directions to contact and deflect the strip 20. This swinging of the movable bars 16 and 18 is effected by swinging the operating handle 11, and thereby causing the segmental rack 12 to act upon pinion 13 for rotating the bar or shaft 9. Simultaneously the bar or shaft 8 is rotated in an opposite direction because of the intermeshing of its pinion 14 with the pinion 15 on shaft 9. This action obviously swings the bars 16 and 18 in opposite directions through the arcs A—B and B—B.

Figure 4 of the drawings illustrates the beginning of the operation described above; with the movable bar 18 already in contact with the strip 20, and the other surface of the strip in direct contact with the bars or shafts 8 and 9.

Figure 5 of the drawings illustrates a position of the movable bars in which they are swung still further in opposite directions, with the bar 16 also serving to deflect the strip 20. It will be understood that this position of the movable bars places the strip under a tension which is sufficient for certain grades and thicknesses of metal.

Figure 6 of the drawings illustrates a further progression of the swinging operation; with the arms 16 and 18, and the portions of the strip deflected thereby, brought into relatively close relation to each other. In this position the strip 20 is obviously placed under greater tension than in the position illustrated in the preceding figure,

owing to the greater deflection of the strip.

These positions of the arms are those which are desirable when the strips being rolled are composed of aluminum or some other metal the surface of which is subject to injury by excessive friction.

Figure 7 of the drawings shows the final position of the swinging bars, as shown also in dotted lines in Figure 1 of the drawings. In this position the bars 16 and 18 have been swung past each other, so that the strip is brought into contact with itself to create a frictional drag against the pull of the rolls. It will be noted that this wrapping of the strip on itself is on the movable bar 18. It will be further seen that throughout an area X—X two layers of the strip are in mutual contact, and that throughout the area X—Y three layers of the strip are in mutual contact.

If the movable bars 16 and 18 are swung into a position intermediate the positions shown in Figures 6 and 7 two layers of the strip 20 may be brought into mutual contact to create a frictional drag, without bringing three layers thereof into mutual contact. Various other positions of the bars intermediate those actually illustrated may also be effected by producing intermediate positions of the swinging bars.

The latter positions of the movable bars are those which are desirable when the strips being rolled are composed of brass, steel, copper, or other metal the surface of which is not particularly subject to injury by friction thereon.

Means are provided for locking the swinging bar in any of the positions shown, or in any intermediate position. Such means comprise a locking pin 21, held in a bracket 22 on the side arm 1 of the bridle and arranged to engage between the teeth of the pinion 13 to hold it and the bar or shaft 9 against rotation. By holding the shaft 9 against rotation, the shaft 8 is also held because of the intermeshing of pinion 14 thereon with pinion 15 on the shaft 9. A coiled spring 23 in bracket 22 serves to hold the locking pin in engagement with pinion 13, and the locking pin is provided with a handle 24 for withdrawing it from engagement therewith.

The apparatus described above is so arranged that the strip passing through the rolling mill may be placed under any desired tension or subjected to either a light or heavy frictional drag. It is thus adapted for use in rolling metal strips of varying thickness and stiffness, and for rolling strips composed of metals which vary widely in their qualities and the manner in which they are most desirably handled.

The form of the apparatus illustrated in Figure 8 of the drawings is adapted particularly for use in the bridling of bars of

round or rectangular cross section. For this purpose the apparatus shown in the preceding drawings may simply be provided with bridle bars which have therein semi-circular 5 or rectangular grooves for receiving the bar to be rolled.

As shown in this figure of the drawings, however, the apparatus is contracted and comprises bridle bars 7^a; 8^a; 9^a; 16^a and 18^a 10 of lesser length than the form designed particularly for the bridling of flat bars or strips, because bars of any great length are unnecessary for the purpose for which this 15 form of the apparatus is designed. The short bridle bars of this form of the apparatus are shown provided with semi-circular grooves 25 for receiving a round bar which is to be placed under tension. The short bridle bar shown in Figure 9 of the drawings 20 is also grooved, but this groove 26 is rectangular in section for the reception of rectangular bars.

With this form when put to the use for which it is intended, the threading of the bar is accomplished as shown in the diagrammatic Figure 3 of the drawings. The actual bridling is accomplished with the movable bars 16 and 18 in the positions shown in Figures 4, 5, and 6 of the drawings. Obviously it would be impracticable to produce the frictional drag shown in Figure 7 of the drawings, or produced by a position of the movable bars intermediate the positions illustrated in Figures 6 and 7 thereof.

25 The apparatus is strong, compact, and simple, and it may be readily operated by a simple movement of the operating handle in one direction to swing the movable bridle bars in opposite directions for securing the tensioning of the strip which may be most desirable for the speed of the rolls and the character of the strip being passed therethrough.

The advantages of the device as hereinabove set forth, together with numerous other 45 advantages, will be readily appreciated by those skilled in the art to which the invention pertains. As the device described and illustrated is, moreover, susceptible of a number of modifications without departing from the spirit of the invention embodied therein, the scope of the invention is to be restricted 50 only by the limitations contained in the claims appended hereto.

What we claim is:

55 1. In bridling apparatus for use in conjunction with rolling mills a pair of bridle bars mounted and arranged to be swung in opposite directions.

2. In bridling apparatus for use in conjunction with rolling mills a pair of bridle bars mounted and arranged to be swung simultaneously in opposite directions.

60 3. In bridling apparatus for use in conjunction with rolling mills a pair of bridle bars each mounted to swing about a dif-

ferent axis and arranged to be swung to describe arcs of circles of different radius; whereby the bars may pass each other when swung.

4. In bridling apparatus for use in conjunction with rolling mills a pair of bridle bars mounted and arranged to be swung in opposite directions, and means for simultaneously actuating said bars. 70

5. In bridling apparatus for use in conjunction with rolling mills a pair of bridle bars mounted and arranged to be swung simultaneously in opposite directions, and means for locking said bars in adjusted position. 75

6. In bridling apparatus for use in conjunction with rolling mills a pair of bridle bars each mounted to swing about a different axis and arranged to be swung to describe arcs of circles of different radius, whereby 85 the bars may pass each other when swung; and means for simultaneously actuating said bars.

7. In bridling apparatus for use in conjunction with rolling mills a pair of bridle bars mounted and arranged to be swung in opposite directions, means for simultaneously actuating said bars, and means for locking said bars in adjusted position. 90

8. In bridling apparatus for use in conjunction with rolling mills a pair of bridle bars each mounted to swing about a different axis and arranged to be swung to describe arcs of circles of different radius, whereby 95 the bars may pass each other when swung; means for actuating said bars; and means for locking said bars in various positions along the arcs described thereby. 100

9. Bridling apparatus for use in conjunction with rolling mills comprising a plurality of stationary bridle bars, a plurality of movable bridle bars each mounted to swing upon one of said stationary bars as an axis, and means for simultaneously swinging said 105 movable bars. 110

10. Bridling apparatus for use in conjunction with rolling mills comprising a plurality of stationary bridle bars each mounted to swing upon one of said stationary bars as an axis and arranged to describe 115 arcs of circles of different radius when swung, and means for actuating said swinging bars.

11. Bridling apparatus for use in conjunction with rolling mills comprising a plurality of stationary bridle bars, a plurality of movable bridle bars each swingingly mounted upon one of said stationary bars, and means for actuating said movable bars. 120

12. Bridling apparatus for use in conjunction with rolling mills comprising a plurality of stationary bridle bars, a plurality of movable bridle bars each mounted upon one of said stationary bars and arranged to be swung to describe arcs of circles of dif- 125 130

ferent radius, and means for actuating said movable bars.

13. Bridling apparatus for use in conjunction with the rolling mills comprising a plurality of stationary bridle bars, two movable bridle bars, arms whereby each of the movable bridle bars is mounted upon one of said stationary bars, the arms by means of which one of said arms is mounted being 10 longer than the arms of the other thereof.

14. Bridling apparatus for use in conjunction with rolling mills comprising a plurality of stationary bridle bars, two movable bridle bars, curved arms whereby 15 each of the movable bars is swingingly mounted upon one of said stationary bars, the arms of the different movable bars being of such relative length and form and so mounted on the stationary bars that the 20 movable bars may pass each other when simultaneously swung in opposite directions, and means for actuating said movable bars.

15. Bridling apparatus for use in conjunction with rolling mills comprising two 25 rotatably mounted bridle bars, means and connections for simultaneously rotating said bars in opposite directions, and two bridle bars rigidly mounted upon said rotatable bars and arranged to be swung thereby.

16. Bridling apparatus for use in conjunction with rolling mills comprising two rotatably mounted bridle bars, means and connections for simultaneously rotating said bars in opposite directions, and two bridle bars rigidly mounted upon said rotatable bars by arms of different length; whereby said last named bars are swung to describe arcs of circles of different radius. 35

17. Bridling apparatus for use in conjunction with rolling mills comprising two 40 rotatably mounted bridle bars, means and connections for simultaneously rotating said bars in opposite directions, and two bridle bars rigidly mounted upon said rotatable bars by arms of different length, whereby 45 said last named bars are swung to describe arcs of circles of different radius; said arms being of such form and so mounted on the rotatable bars that the swinging bars may pass each other when swung in opposite 50 directions.

In testimony whereof, we hereunto set our hands.

JOSEPH G. BAIN.
LASZLO M. STEMPLE.
